UNITED STATES PATENT OFFICE

1,997,190

CONTROL SWITCH

Malcolm E. Henning, Des Moines, Iowa, assignor
to Penn Electric Switch Co., Des Moines, Iowa,
a corporation of Iowa

Application July 3, 1930, Serial No. 465,595

1 Claim. (Cl. 200—88)

An object of my invention is to provide an automatic control switch having general utility and provided with primary and secondary control circuits, one of which has a delayed action 5 with respect to the other one.

A further object is to provide a control switch which may be used for the blower motor of an oil burner whereby when the supply of oil is automatically shut off from the burner, the blower 10 continues to operate for a predetermined period of time to clear the combustion chamber of any further flow of oil or vaporized oil which might collect therein and cause an explosion upon the automatic control devices for the oil burner again 15 rendering it operative.

A further object is to provide in connection with a solenoid opened oil supply valve controlled by a primary circuit control device, a secondary circuit control device for the blower motor for 20 causing it to continue to operate a predetermined length of time, after the primary control device has allowed the oil supply valve to close. More particularly, it is my object to provide in connection with a solenoid opened oil supply 25 valve, a blower motor switch consisting of a switch arm operated by the solenoid armature and connected in the circuit of the blower motor, a thermostatic latch being provided for maintaining the switch arm in closed circuit position 30 during energization of the solenoid and simultaneous energization of a heating element surrounding the thermostatic latch bar whereby the switch arm may be retained by the thermostatic bar in closed circuit position, after the solenoid 35 and heating element have been deenergized and until the heating element has cooled to such a point that it will unlatch the switch arm and allow it to move to open circuit position.

Still a further object is to provide magnetic 40 means in connection with the switch arm for holding the switch contacts in engaged position and for assisting in quick separation of the contacts when the switch arm moves to open circuit position.

Still a further object is to provide a contact 45 on the switch arm movable with respect thereto so as to compensate for different current voltages supplied to the solenoid, to compensate for variations in the dimensions of parts of the control device, to compensate for an amount of play required between the switch arm and the thermostatic latch and to assist in quick separation of the switch contacts.

With these and other objects in view my invention 55 consists in the construction, arrangement and

combination of the various parts of my device, whereby the objects contemplated are attained, as hereinafter more fully set forth, pointed out in my claim, and illustrated in the accompanying drawing, in which:

Figure 1 is a perspective view of my oil burner blower motor control device.

Figure 2 is a vertical central sectional view of the same showing it in inoperative position.

Figure 3 is a side elevation of a portion of the 10 device showing it in operative position and

Figure 4 is a diagrammatic view showing a primary control device, my oil burner blower motor control device, and oil supply valve and a blower motor.

On the accompanying drawing, I have used the reference numeral 10 to indicate a plate or other support usually included in the construction of an oil burner for furnaces or the like. Oil burners of the kind for which my control 20 device is designed include an oil valve 12, the needle 14 of which is connected with an armature 16. The armature 16 is slidable within the core 18 of a solenoid coil 20 and is adapted to be raised whenever the coil is energized for opening the oil valve 12 and supplying oil to the oil 25 burner.

A room thermostat 22 (see Figure 4) is usually connected in the circuit of the solenoid coil 20 for energizing the same whenever the temperature of a room to be heated by the oil burner lowers to a predetermined degree and the room thermostat opens the circuit when the temperature rises to a predetermined degree.

A casing 24 surrounds the solenoid coil 20 and 30 supports what I shall term a secondary control switch, considering the room thermostat 22 as a primary control switch.

The secondary control switch includes a switch arm 26 pivoted on a pin 28. A contact plate 30 40 has a finger extending into a socket 32 in the switch arm 26 and carries a contact 34. Slight swinging movement of the plate 30 may be had relative to the switch arm 26 because of the finger extending into the socket 32.

A screw 36 extends through an opening in the contact plate 30 for preventing side movement of the plate relative to the switch arm 26 and yet allowing up and down movement of the plate relative to the arm. A spring 38, interposed between the head of the screw 36 and the contact plate 30, normally retains the plate against the switch arm, as shown in Figure 2.

A stationary contact 40 is mounted on a stationary contact plate 42. The plate 42 is held in 55

position on a boss 44 by means of a screw 46. The screw 46 also retains a permanent magnet 48 in position on the boss 44 to act upon armature portions 50 of the contact plate 30. The stationary contact plate 42 is suitably insulated from the boss 44, the screw 46 and the magnet 48 by insulation washers and sleeves, as shown in Figure 2.

An operative connection is provided between the armature 16 and the switch arm 26, as will now be described. A post 52 extends upwardly from the armature 16 through an enlarged opening 54 in the switch arm 26. A leaf spring 56 is secured to the switch arm 26 and extends over the opening 54. The spring 56 is adapted to be engaged by the post 52 whenever the same moves upwardly, as shown, for instance, in Figure 3.

A weight 58 is provided for the switch arm 26 to normally retain it in open circuit position. The weight 58 is pivoted to the switch arm 26 by means of a pin 60. The weight 58 has stop shoulders 62 and 64 adapted to engage a flange 65 on the solenoid casing 24 to limit movement of the switch arm 26 in either direction.

A thermostatic latch bar 66 is provided for the switch arm 26 and is secured to the base 10 by a screw 68. An adjusting screw 70 is provided for adjusting the position of the latch 66 relative to the portion of the switch arm 26 with which it coacts and for consequently adjusting the timing of the operation of the thermostatic latch, as will hereinafter be more fully set forth. The heating element 12 is wrapped around the thermostatic latch bar 66.

35   *Practical operation*

Referring to Figure 4, the oil burner blower motor control is shown in inoperative position. When the room thermostat 22 calls for heat, it will close the current supply through the solenoid coil 20 and the heating element 12 whereby the oil valve 12 will be opened due to the action of the solenoid 20 on the armature 16. The post 52 will engage the spring 56 for closing the switch contacts 34 and 40, as shown in Figure 3, the switch arm then being in the dotted line position shown in Figure 2. This will establish a circuit through the blower motor 74 so that both oil and air are supplied to the oil burner.

The effect of the heat from the heating element 12 on the thermostatic bar 66 will flex the bar to the dotted line position shown in Figure 2.

When the room thermostat 22 moves to open circuit position, the oil valve 12 will immediately

close, the switch arm 26 will drop down against the end of the thermostatic bar 66, but the contacts 34 and 40 will still remain in engagement with each other. This causes continued operation of the blower motor 74 to clear the combustion chamber of the furnace of any oil or explosive vapor which might be therein.

After a short period of time, the thermostatic latch bar 66 will flex to the solid line position shown in Figure 2 and allow the blower motor circuit to be broken.

The contact plate 30 is mounted movable relative to the switch arm 26 so that when the armature 16 raises to the position shown in Figure 3, the contacts 34 and 40 may first engage and then the switch arm 26 may be moved further so as to space the arm above the upper end of the latch bar 66, as shown in dotted lines in Figure 2. Then when the solenoid 20 is subsequently deenergized, the switch arm 26 will drop to a position resting on the top of the latch bar 66, but the contacts 34 and 40 will still remain in engagement with each other. Thus it is seen that the movability of the contact plate 30 relative to the switch arm 26 is important.

The leaf spring 56 provides a resilient operative connection between the plunger 16 and the switch arm 26 whereby to prevent vibration being imparted from the post 52 to the switch arm. This is especially desirable when alternating current is used.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

In a control switch, a pivoted switch lever, electro responsive means for moving the same, a leaf spring element carried by and secured to said switch lever, said electro responsive means being engageable therewith when energized, whereby said lever is moved by tension of said leaf spring, a movable contact carried by said switch lever, a stationary contact for coaction therewith, one of said contacts being movable under tension with respect to its means of support, and a thermal latch for said switch lever in the position it assumes when said electro responsive means is energized.

MALCOLM E. HENNING.
